UNITED STATES PATENT OFFICE.

PERCY M. GRIGGS, OF FORT BRIDGER, WYOMING.

THEATER-CHAIR ATTACHMENT.

1,250,857.

Specification of Letters Patent. Patented Dec. 18, 1917.

Application filed September 23, 1916. Serial No. 121,741.

To all whom it may concern:

Be it known that I, PERCY M. GRIGGS, a citizen of the United States, residing at Fort Bridger, in the county of Uinta and State of Wyoming, have invented certain new and useful Improvements in Theater-Chair Attachments; and I do hereby declare the following to be a full, clear, and exact description of the invention, such as will enable others skilled in the art to which it appertains to make and use the same.

This invention relates to a chair attachment designed particularly to be associated with a theater chair and adapted to hold a hat, coat or wrap, and a cane or umbrella, and an object of the invention is the provision of such an attachment that will be of simple and durable construction, can be conveniently applied to the chair, and when not in use can be collapsed so as to occupy a minimum amount of space.

Other objects will appear and be better understood from that embodiment of my invention of which the following is a specification, reference being had to the accompanying drawings forming a part thereof, in which:

Figure 1 is a rear view of a chair, showing the coat and umbrella holding device mounted thereon,

Fig. 2 is a vertical side elevation of the chair, showing the hat holding device on the seat, and also the coat and umbrella holding device,

Fig. 3 is a section, taken on the line 3—3 of Fig. 2,

Fig. 4 is a section, taken on the line 4—4 of Fig. 2,

Fig. 5 is a sectional detail view of the holding means for holding the hat holder in unfolded position.

Referring to the drawings in detail, a theater chair of the usual construction is shown consisting of the supporting legs A, hinged seat B and back piece C. Located beneath the seat B is a hat holder which consists of front and rear walls 1 and 2, formed of rectangular shaped members formed preferably of wood, or the like, and opposite side walls 3 and a bottom wall 4. The walls 3 and 4 are formed of a plurality of intersecting and pivotally connected levers, which are connected to the respective walls 1 and 2, and are of the lazy tongs construction, so that the entire hat holding structure can be folded or unfolded, as de-

sired. The rear wall 2 is stationary and is secured in place in any suitable manner, and the said rear wall 2 and the front wall 1 are further connected to each other by means of contractile springs 5, which are extended, when the front wall 1 is moved to the position shown in Fig. 2, and when the front wall 1 is released the springs 5 contract and move the front wall 1 in the direction of the rear wall 2, so as to present a comparatively small structure that will occupy a minimum amount of space. Positioned exteriorly of the sides 3 and mounted on the rear wall 2 is a pair of upright members 6, which are spaced from the rear wall 2 and have their upper and lower ends bent to provide attaching portions which have connection with the rear wall 2. A pair of pivoted rods 7 are located exteriorly of the sides 3, and are inclined inwardly and upwardly, and have their lower or outer ends pivotally connected in any suitable manner to the front wall 3, and their inner ends provided with eyes 8 that are slidably mounted on the upright 6. When the hat holder is unfolded and the front wall thereof assumes the position shown in Fig. 2, the inner ends of the rods 7 will be in their lowermost position, as shown in Figs. 2 and 5, and will be held against upward movement by means of lugs 9, which are formed on the eyes and adapted to be received by notches 9^a in the uprights 6. When it is desired to collapse the hat holder the rods 7 are moved upwardly so as to withdraw the lugs from the notches in the uprights 6 and the springs 5 will then pull the front wall 1 inwardly to a position where it will lie in close proximity to the rear wall 2.

A supporting bar 9^b is mounted on the back C of the chair, at the rear side thereof and adjacent the upper end of the back, and is adapted to support a coat, or the like. A resiliently mounted frame 10^a is positioned on the back C of the seat and incloses a panel 10^b formed of intersecting wires, as shown more particularly in Fig. 1 of the drawings. Arms 10, formed of spring metal have connection with the sides of the frame 10^a and have their opposite ends bent downwardly and fitted in apertured lugs 11 secured to the rear side of the back B. The frame 10^a when in normal position lies in close relation with the back C, and when a coat, or similar garment is suspended from the bar 9^b, the frame 10^a will prevent acci-

dental removal of the garment from the bar 9^b. The frame 10^a may also serve as a garment-holder, the garment being folded over the upper edge of the frame. The springs 10 permit the frame being pulled outwardly, to the position shown in Fig. 4, so as to admit of the garment being suspended either from the bar 9^b or folded over the upper end of the frame and when the frame is released 10 the springs 10 will move the frame into close relation with the back C of the chair. A vertically disposed cylindrical shaped receptacle 12 is mounted on the outer side of the frame 10^a, and serves as a cane or umbrella 15 holder.

It is evident that various changes might be resorted to in the construction, form and arrangement of the several parts without departing from the spirit and scope of my invention; hence I do not wish to limit myself strictly to the structure herein described and claimed.

Having thus described my invention what I claim as new, is:

5 1. An article holding device for a chair consisting of a stationary wall, a movable wall adapted to normally lie in close proximity to the stationary wall and to be moved outwardly to admit of an article being positioned in rear thereof, uprights carried by the stationary wall, rods interposed between the stationary wall and the movable wall and

adapted to prevent inward movement of the movable wall when the latter is in outward position and having their forward ends pivoted to the stationary wall and their rear ends slidably mounted on the uprights, and means for holding the last-mentioned ends of the rods against movement when the rods are in operative position.

35 2. An article holding device for a chair consisting of a stationary wall, a movable wall adapted to normally lie in close proximity to the stationary wall and to be moved outwardly to admit of an article being positioned in rear thereof, vertically positioned substantially U-shaped members secured to the stationary wall, rods pivotally secured to the lower portion of the movable wall and having the outer ends thereof slidably engaging the U-shaped members, said U-shaped members having a notch formed in the lower portion thereof for receiving the outer ends of the rods to normally hold the movable wall in an extended position, and 40 spring means for normally holding the movable wall in close proximity to the stationary wall.

45 In testimony whereof I affix my signature in presence of two witnesses.

PERCY M. GRIGGS.
